UNITED STATES PATENT OFFICE.

FRED A. DENNETT, OF SHEBOYGAN, WISCONSIN.

DESIGN FOR A CHAIR-SEAT FRAME.

SPECIFICATION forming part of Design No. 23,905, dated December 25, 1894.

Application filed November 30, 1894. Serial No. 530,493. Term of patent 7 years.

To all whom it may concern:

Be it known that I, FRED A. DENNETT, a citizen of the United States, residing at Sheboygan, in the county of Sheboygan and State of Wisconsin, have invented and produced a new and original Design for Chair-Seat Frames; and I do declare the following to be a full, clear, and exact description of the same, reference being had to the accompanying drawing, forming a part thereof.

The said drawing represents an end view of a chair-seat frame embodying my new design.

My design relates to the new and original shape or configuration of the article.

15 The leading features of this design for a chair-seat frame consist in a general ogee-shape of the upper bar thereof, and in the configuration of the lower bar thereof, of a generally semi-circular outline interrupted 20 by low rounded swellings on the under side, and more abrupt and pointed projections on the upper side, and in the general configuration of the rods or supports connecting the said upper and lower bars.

25 A represents one of the said upper bars, and as stated is of a general ogee-shape in external configuration, having straight ends.

B represents one of the said lower bars, of a generally semi-circular outline, the upper 30 side of the same, at each end, being formed on the line of an ogee, as shown at *aa*, from the highest points of which, *bb*, the outline of the said upper side of the bar follows rounded convex lines *cc* to the points *dd*, between 35 which the upper side of the central portion of said bar follows the arc of a circle, as shown at *ee*. Between the points *ff* the under side

of the said central portion of the lower bar follows the arc of a circle as shown at *g*, parallel to the arc *e* above, while from these 40 points, outward, the outline of said under side continues in low or shallow rounded convex swellings *hh*, and beyond these in somewhat deeper and longer rounded concave shallow swellings *ii* terminating in rounded semi-circular convex ends *jj* blending in outline with the hereinbefore described ogee-lines *aa*. The outer side surface of this lower bar is ornamented with a series of annular depressions *kk*.

45 The rods or supports *mm* which rise from the central portion of the lower bar and extend to the upper bar are cylindrical in outline and vertically disposed. At the front of the chair-seat frame is another rod *n* of cylindrical outline having a central portion *o* of spherical shape, above and below which are similar spherical enlargements *p q* of like shape but of less diameter than that of the central portion *o*. At the rear of the chair- 50 seat frame are two other inclined rods *r* and *s* arranged so as to incline in a direction opposite to that of the inclination of the front rod *n*, but similarly ornamented by the spherical enlargements *o p q*.

55 60 65 What I claim is—

The design for a chair seat frame substantially as shown and described.

In testimony whereof I affix my signature in presence of two witnesses.

FRED A. DENNETT.
